UNITED STATES PATENT OFFICE.

HARRY M. SPRECHER, OF EPHRATA, PENNSYLVANIA.

ROLL-MEASURER.

1,072,268.

Specification of Letters Patent. Patented Sept. 2, 1913.

Application filed August 13, 1912. Serial No. 714,937.

To all whom it may concern:

Be it known that I, HARRY M. SPRECHER, a citizen of the United States, residing at Ephrata, in the county of Lancaster and State of Pennsylvania, have invented new and useful Improvements in Roll-Measurers, of which the following is a specification.

This invention relates to roll measures, the object in view being to provide a roll of fabric, such as wire fencing, with a permanently attached graduated measuring tape, whereby in dispensing the fabric or wire fencing the proper length thereof may be determined by referring to the attached measuring tape, thereby greatly facilitating the work of the retailer.

With the above and other objects in view, the invention consists in the construction, combination and arrangement of parts, as will be hereinafter more fully described, illustrated in the accompanying drawings, and pointed out in the claims hereunto appended.

In the drawings: Figure 1 is a perspective view of a section of wire fencing, showing the present invention applied thereto. Fig. 2 is a longitudinal section through the same on the line 2-2 of Fig. 1.

Referring to the drawings, 1 designates a section of fabric, such as wire fencing, the same being usually shipped in rolls and requiring to be measured off with a tape line or rule of some kind, in order to dispense the number of feet required.

In carrying out the present invention, in the preferred form thereof, I employ a tape line 2 which extends lengthwise of the fabric, as illustrated in Figs. 1 and 2, said tape line embodying two plies or thicknesses 3 and 4, one or both of which is graduated, as shown at 5, or in other words laid off in feet and inches or any other measuring symbols.

The two plies or strips 3 and 4, for the sake of economy, are composed of paper, and said strips are placed on opposite sides of the fabric and pasted or gummed together within the openings of the meshes of the fabric, as clearly shown in the longitudinal section, Fig. 2. This has the effect of attaching the tape line permanently to the fabric, so that it cannot become displaced in the automatic handling of the same.

When the tape is combined with a roll of fabric in the manner above described, it will be seen that the measuring off of a certain number of feet or yards of the fabric will be greatly facilitated, thus saving considerably in the time of the retailer, and also assuring the purchaser of the correct amount of fabric required by him.

What is claimed is:

1. The combination with a roll of open mesh fabric such as wire fencing, of a graduated measuring tape extending lengthwise of the fabric and embodying two plies or strips located on opposite sides of the fabric and secured together within the mesh openings.

2. The combination with a roll of open mesh fabric such as wire fencing, of a graduated measuring tape extending lengthwise of the fabric and embodying two plies or strips located on opposite sides of the fabric and pasted together within the mesh openings.

In testimony whereof I affix my signature in presence of two witnesses.

HARRY M. SPRECHER.
